DEVICE FOR CONDITIONING AIR

Frank A. Whiteley, Minneapolis, Minn.

Application September 11, 1931, Serial No. 562,249
Renewed January 4, 1934

REISSUED

13 Claims. (Cl. 257—8)

My invention relates to a method and device for conditioning air in rooms, and has for its object to provide a simple and efficient device for concealed installation in the wall of a room between the studding, which by means of connections with cooling and heating devices in the basement, may be alternately operated to furnish warm moist air to a room in winter during cold weather, and cold dry air in summer or during hot weather.

- 10 It is one object of my invention to provide a method of conditioning air in rooms which consists in removing a portion of the wall of the room through at least one face thereof to form a recessed channel therein extending vertically from a point at or near the floor to a point at or near the ceiling, introducing a casing into said recess of like vertical extent having openings into the room at the top and bottom thereof, forming an insulating cover to a wall of said casing having 20 its surface in the plane of the wall of the room and decorating the same so as to conceal said casing, causing air to enter at one opening and move through the casing to discharge through the other opening, and conditioning the air as it is moved.
- 15 It is an object of my invention to provide an air conditioning device for the purpose stated having upper and lower openings therein, together with means for alternately circulating air to cause it to enter through the lower opening and discharge from the upper opening, or to enter through the upper opening and discharge through the lower opening.

The full objects and advantages of my invention will appear in connection with the detailed description thereof, and the novel features of my inventive idea will be particularly pointed out in the claims.

In the drawings illustrating an application of my invention in one form,

- 40 Fig. 1 is a front elevation view of my invention applied to the wall of a room with structural parts of the building in section, and the position of the air conditioning member shown by dotted lines. Fig. 2 is a sectional elevation view similar to Fig. 1. Fig. 3 is a sectional plan view on line 3—3 of Fig. 2. Fig. 4 is a sectional plan view on line 4—4 of Fig. 2. Fig. 5 is a sectional side elevation of the central portion of the air conditioning device adjacent the blower mechanism. Fig. 6 is a similar view taken at the lower end of the air conditioner. Fig. 7 is a side sectional view of a portion of one of the heat exchangers showing the oblique or downward trend of the tubes connecting the headers.

55 My invention embodies a casing preferably of

sheet metal having front and rear walls 10 and 11 and end walls 12 and 13, with a top wall 14 and a bottom wall 15 which last is in the form of a funnel with a connection 16 for a drain pipe 17. The casing forms an elongated rectangular box 5 closed excepting for top and bottom openings protected by lower register 18 and upper register 19, at the floor and near the ceiling, respectively, as shown in Fig. 1. To the front 10 of this box is secured a plate 20 of some type of insulating material. The box is adapted to be slipped between two studdings 21 and 22 forming a support in the wall and is secured permanently in place by nails, screws or other fastening members indicated at 23 which enter the studding members 21 and 22 and 15 which bring the face of the plate 20 even with the face of the plaster 24, so that canvas and paper indicated at 25 may entirely conceal the joint 26 where the plaster has been cut away.

Within the casing above described are permanently positioned heat exchangers made according to the process of my co-pending application, Serial Number 545,940 filed June 22, 1931, embodying headers 26' and 27 of generally rectangular cross section, fin plates 28 and connecting tubes 29, the tubes being fused into the fin plates and integrated to the headers into which they open, in accordance with the principles of said process application, excepting that in the present invention the tubes 29 do not extend between and at right angles to the headers 26' and 27, but, rather extend obliquely between said headers so that all of said tubes have a downward slant from the headers 26' to the headers 27, as clearly shown in Fig. 7. 35

One of said heat exchangers is shown in Fig. 2 positioned at the upper part of the casing and having an inlet hot water or steam pipe 30 connected with the bottom of header 26 to an outlet steam or hot water pipe 31 connected with the 40 bottom of header 27, these hot water or steam pipes going to the customary boiler (not shown) in the basement of the building. Immediately below the upper heat exchanger is a blower chamber 32 which will be hereinafter described. 45 And below said blower chamber is a group of three heat exchangers connected together in series in accordance with my aforesaid application, with a pipe 33 for conveying a heat absorbing medium from compressor means in the basement, not shown, to the lower header 27 from which said medium goes to the lower header 26' and from the lower header 26 through connection 34 to the middle header 26' and from there across to the middle header 27 and from the mid- 50 55

die header 27 through connection 35 to the upper header 27 and from upper header 27 across to the upper header 26 and therethrough opening 36 and discharge pipe 37 back to the compressor 5 in the basement. Steam or hot water pipes 38 and 39 and the cool fluid return pipe 37 and water pipe 38 all pass downward through a chamber 39 formed by a partition 40 spaced from the end wall 12 of the casing, as clearly shown in Fig. 4. 10 The pipe 37 has a horizontal portion 41 overlying the fin plates 28 of the air cooling heat exchanger. An automatic valve 42 controlled by a solenoid in circuit with the motor of the blowers hereinafter to be described, admits water to pipe 15 37 and its extension 41 when the blowers are in operation for heating the room. The water is delivered upon the fin plates 28 and flows downwardly along the surfaces of said fin plates where it is impinged by the upward movement of air 20 and takes up sufficient water effectively to humidify the air of the room and of other rooms of the house.

Ordinarily the humidifier will be used only in connection with the heating means when the 25 blowers are set to move the air upwardly and discharge it from the upper opening. In this manner, because of the large amount of wet surface contacted by the moving air, the air will reach the blowers substantially saturated. But it will 30 be the cooler air of the room and will have been further cooled by that evaporation to a point well below room temperature, so, as it is immediately thereafter heated, it cannot overhumidify the higher temperature air of the room, but will ordinarily supply just enough moisture to keep the 35 air at the higher room temperature just sufficiently and never too greatly, humidified. There may be times, however, when, owing to excessive dryness of the air, during severe cold 40 spells, for example, it may be desirable to supply a greater amount of moisture to the air, and in such cases the blowers may be reversed, thus drawing the air from the heating heat exchanger, and driving hot air through the passages and over 45 the wet surfaces of the plates in the cooling heat exchanger, thereby furnishing the requisite added moisture. And it is further desirable, in the summertime when the cooling heat exchanger is normally in operation, periodically to blow hot 50 air over the cooling heat exchanger surfaces to dry them and prevent formation of slimes or other growths which might tend to clog these passages, and to keep the passages clean.

The air moving arrangement comprises a motor 43 and centrifugal blowers 44, 45 at the sides of said motor, in the blower chamber 32. As best shown in Figs. 4 and 5, this blower arrangement is mounted within a rotatable drum having front and rear walls 46 and 47 and a transverse partition 48, all being secured upon a central shaft 49 held in the journal 50 at the side of the casing and adapted to be rotated by a handle 51. The discharge of the blowers 52 and 53 extends through the transverse partition 48, as best 55 shown in Fig. 2.

The operation of my device will be readily understood from the foregoing description. When in the position shown in Fig. 2, the blowers will draw air through lower register 18 and the casing 70 below, which will pass through the fins of the cooling heat exchangers taking up moisture from the water films thereon and be driven through the fins 28 of the heating heat exchanger and discharge the air warm and moist through the 75 upper register 19. When it is desired to use the

device for cooling, the air-moving means is rotated 180°, when air will be drawn in through the register 19, pass downwardly through the cooling heat exchangers and discharge into the room through the lower register 18, being cooled on the way. The water which is condensed from this air on the cold fin plates 28 will gravitate to the bottom and discharge from the system through the pipe 12, and any excess water used in humidifying will find exit by the same means.

The advantages of my invention will be apparent from the foregoing description. The device is easily installed in houses wherein steam or hot water heating appliances are available and already in use. When the same has been installed, 10 it will be entirely invisible, except at the register openings at top and bottom. It will operate to deliver warm moist air in winter or cold weather, at the top, taking into the system the cold air at the bottom, and in summer or in hot weather, 15 it will operate to deliver cold dry air at the bottom and take in the hot humid air at the top. It is cheap to construct, and hence within the means of the ordinary householder.

One advantage of the use of this construction 20 is that in dwelling houses an air conditioner may be placed in each of several rooms, as a living room and a bed room, and be connected to compressor mechanism in the basement by separate leads so that a compressor need be employed only 25 large enough to operate one heat exchanger but may be connected alternatively to either the living room heat exchanger or the bedroom heat exchanger to cool the one in the day-time and the other at night. A further advantage of the air 30 conditioner resides in its use in conditioning the air in offices of large office buildings or in the rooms of apartments in apartment buildings. Separate air conditioners embodying the principles of my invention may be applied to each 35 office or each group of offices, or each room or apartment, and the heating unit supplied with steam from the usual central system and the cooling unit supplied with heat-transferring compressed gases from a large central compressor 40 unit in a manner similar to the distributing and heating medium from a large central heating unit.

I claim:

1. An air conditioner comprising a casing adapted to be positioned in the wall of a room 50 between studding and having top and bottom openings, means in said casing for heating air, means in said casing for cooling air, and means in the casing for moving air adjustably to cause the air to enter the casing at the bottom and 55 discharge from the top when the heating means is in operation, and to enter the casing at the top and discharge from the bottom when the cooling means is in operation.

2. An air conditioner comprising a casing 60 having upper and lower openings, means at the top of the casing for heating air, means at the bottom of the casing for cooling air, a blower between said means, and means for positioning the blower to discharge air upwardly through 65 said heating means and out of the upper opening or downwardly through said cooling means and out of the lower openings.

3. An air conditioner comprising a casing adapted to be positioned in the wall of the room 70 between studding and having top and bottom openings, means in said casing for heating air, means in said casing for cooling air, and means in the casing for moving air through said cooling means and said heating means, and means as- 75

sociated with the cooling means for humidifying the air as it is moved therethrough when the heating means is operative to heat the air.

4. An air conditioner comprising an elongated vertical casing having openings close to the floor and to the ceiling respectively of a room, two sets of heat exchangers therein, means to cause one of said sets to give off heat, means to cause the other set to absorb heat, and means in the casing to move air in opposite directions in said casing for respective delivery through one of said openings of heated air or of cooled air.

5. An air conditioner comprising an elongated casing, two sets of heat exchangers therein, each embodying a multiplicity of vertical fin plates, means to cause one of said sets to give off heat, means to cause the other set to absorb heat, and means to wet the surfaces of the cooling fins when the heating fins are in operation.

6. An air conditioner comprising a casing having contiguous spaced parallel vertical walls, a rotatable table therein between said walls, a blower mounted on said table for moving air through the casing, means to rotate the table in planes parallel to said walls to reverse the direction of movement of the air, and means in the casing for conditioning the air as it is moved.

7. An air conditioner comprising a casing having contiguous spaced parallel vertical walls, a rotatable table in the casing embodying spaced plates substantially engaging said walls and a transverse partition, a blower located between the plates on one side of the partition and discharging on the other side, means to rotate the table to reverse the direction of said discharge, and means in the casing for conditioning the air moved by the blower.

8. An air conditioner, comprising a casing forming a vertical elongated duct adapted to be positioned in the wall of a room between studing and having top and bottom openings near the ceiling and floor, respectively, means in said casing for heating air, means in said casing for cooling air, and a blower in said casing adjustable to cause the air to move through the casing and enter and discharge from the openings in one direction when the heating means is in operation and to move through the casing and enter and discharge from the openings in an opposite

direction when the cooling means is in operation.

9. An air conditioner, comprising an elongated casing having top and bottom openings, a heating heat exchanger and a cooling heat exchanger in said casing, means to cause water to flow down over the exposed surfaces of the cooling heat exchanger to make it serve as a humidifier when the heating heat exchanger is operative, and means located above the cooling heat exchanger to move the air.

10. An air conditioner, comprising a casing having openings at the ends, cooling and heating heat exchangers in said casing, means to cause water to flow over the exposed surfaces of the cooling heat exchanger to make it serve as a humidifier when the heating heat exchanger is operative, and means between the heat exchangers to move the air.

11. An air conditioner, comprising an elongated casing having openings at or near its ends, a heating heat exchanger located towards one end thereof, a cooling heat exchanger located towards the other end and having a wall thereof spaced from a wall of the casing, and inlet and outlet pipes for the heating heat exchanger entering the casing at said last-named end and extending along in the space between said walls.

12. An air conditioner comprising an elongated casing, means in the casing for heating air, a multiplicity of spaced plates forming a corresponding number of parallel passageways extending within the casing, means to move the air to be subject to said heating means and to pass through said passageways, and means to wet the surfaces of said plates while said air is moved.

13. An air-conditioner comprising a casing forming a vertical elongated duct having upper and lower openings, a blower mounted wholly within the casing having an air outlet extending longitudinally of said duct to move the air therethrough, means to shift the position of the blower to direct movement of the air either up or down in said casing to discharge either through the upper or lower openings thereinto, and means in the casing for conditioning the air as it is moved.

FRANK A. WHITELEY.
